UNITED STATES PATENT OFFICE.

THEODORE E. LA FAYETTE, OF WATERTOWN, MASSACHUSETTS, ASSIGNOR TO HOOD RUBBER CO., OF WATERTOWN, MASSACHUSETTS, A CORPORATION OF MASSACHUSETTS.

RUBBER BOOT OR SHOE.

1,249,639.

Specification of Letters Patent. Patented Dec. 11, 1917.

Application filed June 16, 1914. Serial No. 845,501.

To all whom it may concern:

Be it known that I, THEODORE EDWARD LA FAYETTE, citizen of the United States, residing at Watertown, Massachusetts, have invented certain new and useful Improvements in Rubber Boots or Shoes, of which the following is a specification.

My said invention is particularly advantageous in connection with rubber boots designed more especially for use in rough work such, for example, as mining and quarry work, and the object of the invention is to provide protection for the upper at the point where it joins the sole so that separation or breakage of the parts and resultant leakage will be prevented.

Heretofore, so far as I am aware, rubber boots built up in the customary manner and with the rubber outsoles having their edges 10 of reduced thickness and turned up around and vulcanized to the sides of the upper, have not been adapted for work of this character, as the comparatively thin turned-up sole edge tends to become abraded by the 15 rough usage and to separate from the upper, causing the boot to leak; and boots intended for such purposes have had a heavy welt sole applied, usually embodying a layer or outsole of leather, secured in place by welt 20 stitches.

Such boots are, however, more expensive than a rubber boot having the ordinary rubber sole, but by my invention I produce a rubber boot at no more cost than that having the turned over sole edge above referred to, but with the joint between the upper and sole protected so that an article of extreme durability is secured.

In order that my invention may be thoroughly understood, I have appended hereto a sheet of drawings in which

Figure 1 is a sectional perspective of the outsole;

Fig. 2 is a sectional view of the forward 45 or toe portion of the completed boot with the line of junction between the rand and sole indicated by dotted lines.

Referring by reference characters to this drawing, the numeral 1 designates the outsole of the boot, being of rubber compound 50 and of uniform thickness from edge to edge and having the duck or friction fabric layer 1^a on the top thereof terminating inside of the edges of the sole.

The upper indicated at 2 is also made up 55 in the ordinary manner with the inner sole comprising layers of fabric and rubber and the ordinary rag sole, as indicated at 3. At 4 is shown a rand or strip of rubber compound which I apply at the joint, and which 60 in vulcanizing becomes intimately united to the sole and upper and forms a thick sole edge projecting sufficiently far to efficiently protect the upper. By this means I provide an extremely serviceable but economical 65 boot.

My preferred manner of applying the rand is to apply it to the outsole prior to the application of the outsole to the boot, the outsole with its applied rand being thereafter placed in position and secured by the vulcanizing to which the boot is subjected.

The projecting edges of the sole are buffed down to present a smooth appearance.

While I have described my invention 75 more especially in connection with rubber boots, it will be understood that it is applicable to other types of rubber footwear, as, for example shoes known as tennis shoes or sneakers.

Having thus described my invention what I claim is:

A rubber boot having a projecting outsole and a rubber welt completely covering the upper surface of the projecting margin of 85 said outsole and vulcanized thereto and to the upper, thereby thickening the edge of said outsole.

In testimony whereof I affix my signature in presence of two witnesses.

THEODORE E. LA FAYETTE.
